UNITED STATES PATENT OFFICE.

GIOVANNI MONGARDI, OF SOMERVILLE, MASSACHUSETTS.

AUTOMATIC FIREARM.

1,296,204.

Specification of Letters Patent.

Patented Mar. 4, 1919.

Application filed August 9, 1918. Serial No. 249,072.

To all whom it may concern:

Be it known that I, GIOVANNI MONGARDI, a subject of the King of Italy, having declared my intention to become a citizen of the United States, residing at Somerville, in the county of Middlesex and State of Massachusetts, have invented new and useful Improvements in Automatic Firearms, of which the following is a specification.

10 This invention relates to an automatic fire-arm, particularly of the pistol type, including a barrel-carrying and magazine-containing receiver, a slide which is movable rearwardly or retractable both manually and 15 by the force of an explosion, and a firing pin which is retracted and cocked by the retraction of the slide.

The invention is embodied in the several improvements which I will now proceed to 20 describe and claim.

Of the accompanying drawings forming a part of this specification,—

Figure 1 is a side elevation of a pistol embodying the invention.

25 Fig. 2 is a side elevation, on a larger scale, a side portion of the receiver being removed and the slide being projected.

Fig. 3 is a fragmentary view, partly in section and partly in elevation, showing the 30 slide retracted.

Fig. 4 is a side view of certain parts shown by Fig. 2, other parts being omitted.

Fig. 5 is a plan view of the shell ejector shown in elevation in Figs. 2 and 4, and a 35 plan view of the shell-arresting detent.

Fig. 6 is a bottom plan of the receiver and magazine.

Fig. 7 is a section on line 7—7 of Fig. 2.

Fig. 8 is a section on line 8—8 of Fig. 7.

40 Fig. 9 is an enlarged fragmentary view illustrating the operation of the safety device hereinafter described.

Fig. 10 is a section on line 10—10 of Fig. 9.

45 Fig. 11 is a fragmentary sectional view showing the connection between the receiver and the barrel.

Fig. 12 is a fragmentary view illustrating the action of the slide, in engaging a cartridge in the magazine.

The barrel 12 and receiver 13 are connected by a screw-thread connection at 14, (Fig. 11), portions of the barrel and receiver forming an incline 15 which elevates the nose of the upper cartridge in the magazine 16 and guides the cartridge into the barrel.

17 is a slide or slide head fitted to reciprocate on guides in the upper portion of the receiver, the slide being adapted to be retracted or forced rearwardly, both manually 60 and by the explosion of a cartridge. To the slide 17 is attached a rearwardly projecting stem 18 having a cylindrical bore constituting a guide for the firing-pin 19, and a container for the spring 20 which projects said 65 pin, the stem 18 having a longitudinal slot 21 in its under side through which projects a lug 22 on the firing-pin, formed to be engaged by the sear 23 when the firing-pin is retracted. The receiver 13 is provided at 70 its rear end with a guide 18^a in which the stem 18 is movable, and with a fixed abutment 18^b for the spring 20, said abutment extending through the slot 21 and into the bore of the stem.

75 The sear 23 is a resilient hooked arm attached at 24 to the receiver 13 and adapted normally to engage the lug 22. The sear is displaced from the trigger 25 through a bell-crank lever 26 fulcrumed at 27 in the 80 receiver 13, and a finger 28 pivoted at 29 to an ear on the swinging end of the trigger 25, the latter being pivoted at 30 to the guard frame 31. One arm of the lever 26 is provided with a stud 32 bearing on the upper 85 side of the sear, so that the lever is normally held by the sear in the position shown by Figs. 2 and 4. The other arm of the lever 26 projects through a slot in a portion of the wall of the receiver 13, said portion constituting a guide, and the finger 28 is pressed against said wall portion or guide by a spring 33. When the trigger is pulled against the pressure of its spring 34, the finger slides upwardly on said guide and 90 raises the projecting arm of the lever 26, thus depressing the arm having the stud 32, the latter depressing the sear and releasing the firing-pin, which is then projected by its spring to explode a cartridge in its path. 100

The receiver wall is provided with a projection having an inclined face 28^a, arranged to displace the finger 28 and force it out of engagement with the lever 26. The slide 17, which is retracted, as above stated, by the force of the explosion, is provided with a shell extractor composed of a resilient finger 36 attached at 37 to the slide stem 18, and provided with a hook 38 adapted to engage 10 the head of the shell, as shown by Fig. 5.

The slide acts while being retracted, to set a slide-projecting device whereby the slide is automatically projected or returned to its forward position. Said device includes a two-armed spring 40, one arm of which is seated on a portion of the receiver wall and secured thereto by a pin 41. The other or free arm of the spring 40 engages one end of a link 42 which is pivoted at 43, 15 to the shorter arm 44 of a bell-crank lever, which includes a longer arm 45, the outer end of which is held by the spring 40 in engagement with an elongated face on the slide 17, said portion face being substantially 20 perpendicular to the stem 18 and being preferably the bottom of a vertical slot 46 formed in the rear face of the slide, and in a downwardly-projecting arm 46^a on the slide. When the pistol is cocked and the slide projected, as shown by Fig. 2, the arm 45 is in contact with the lower portion of the said perpendicular face. When the slide is retracted by an explosion, the arm 45 is moved to the position shown by Fig. 3, its outer end 25 moving upwardly on the perpendicular face and the shorter arm 44 being depressed and causing the link 42 to depress the free arm of the spring 40 and increase the tension of said spring. The force of the spring now 30 acts through the link 42 and lever arms 44 and 45 to return the slide to the position shown by Fig. 2.

The slide is provided with a downwardly-projecting lug 47, having an incline 47^a at its rear end as best shown by Fig. 12 and formed to slide over the upper cartridge in the magazine 16, and slightly depress the cartridge against the pressure of the usual cartridge-lifting spring 48, when the slide 45 is moving rearward across the upper end of the magazine, this action of the lug being illustrated by dotted lines in Fig. 12. When the slide is in its rear position, the forward end face 47^b of the lug 47 which is substantially perpendicular to the path of the slide, is in position to bear on the rear end of the cartridge which is now raised; as shown by full lines in Fig. 12. The forward movement of the slide, therefore, causes the lug 50 to force the cartridge forward into the barrel, the cartridge sliding up the incline 15 (Fig. 11).

To permit the pistol to be safely carried when loaded and cocked, I provide a safety

device for locking the lever 26 in the position shown by Figs. 2 and 4. Said device includes a locking arm 50 fixed to a stud 51 (Fig. 10), which is journaled in a bearing in one of the sides of the container 13 and is provided with a handle 52 located outside 70 the container. When the locking-arm is in the position shown by full lines in Fig. 9, it is separated from the lever 26. When the locking-arm is turned to the position shown by dotted lines in Figs. 4 and 9, it locks the 75 lever, and prevents firing. The locking-arm is prevented from being accidentally moved from either position to the other by a helical spring 53 (Fig. 10), inserted in an annular 80 groove in the arm and bearing on the bottom of said groove and on an outer side portion of the container 13, said spring acting as a brake to prevent the loose turning of the locking-arm. The magazine 16 is releasably secured to the receiver 13 by a bolt 85 54 slidable in a socket in the lower end of the magazine, and pressed rearwardly by a spring 55 into engagement with a fixed keeper 56 (Fig. 2), at the rear end of the opening provided for the reception of the 90 magazine. The bolt is provided with a knurled push piece 57, which may be the head of a screw engaged with the bolt and projecting through a slot in the lower end of the magazine. The arrangement is such 95 that the bolt must be pressed forward or toward the front side of the receiver to disengage it from the keeper. Provision is thus made for preventing the bolt from being accidentally retracted by the hand of the user 100 in withdrawing the fire-arm from a pocket or other receptacle.

The operation, as will be understood from the foregoing description, is automatic, after the magazine has been charged and the 105 slide has been manually retracted to cock the pistol and cause the slide to engage the upper cartridge in the magazine. To enable the operator to conveniently retract the slide, I provide a hand grip, composed of 110 parallel side portions 59 slidable on opposite sides of the receiver, and a neck 60 connecting the rear ends of the side portions. The forward ends of the side portions 59 are secured to the slide 17 by screws 61 passing 115 through longitudinal slots 62 in the receiver. The neck 60 is secured to the rear end of the receiver stem 18. The external surfaces of the side portions 59 are provided with finger-engaging corrugations 63.

After the slide has been manually retracted and released, it is forced forward by the spring 40 and forces the first cartridge into the barrel, the firing-pin being now engaged by the sear, and the pistol cocked for 120 firing. The explosion of each cartridge retracts the slide and sets the slide-projecting device, which again projects the slide.

The receiver is provided with a fixed detent 66 (Fig. 5), having a shoulder 67, arranged to arrest the shell (withdrawn by the extractor 36) in position to escape through the usual shell outlet, not shown.

I claim:

1. An automatic fire-arm comprising a magazine-containing receiver, a barrel rigidly connected therewith, said receiver being provided with a guide and with a fixed spring abutment at its rear end, a slide movable in the receiver and including a head and a stem projecting rearwardly from the head and provided with a longitudinal bore and with a longitudinal slot receiving said abutment, a firing-pin movable in said bore and provided with a sear-engaging lug projecting through said slot, a spring interposed between said pin and abutment, a sear adapted to normally engage said lug, a spring-pressed trigger, trigger-operated sear-displacing means, and a slide-projecting device adapted to be set for action by the retraction of the slide.

2. An automatic fire-arm comprising a magazine-containing receiver, a barrel rigidly connected therewith, said receiver being provided with a guide and with a fixed spring abutment at its rear end, a slide movable in the receiver and including a head and a stem projecting rearwardly from the head and provided with a longitudinal bore and with a longitudinal slot receiving said abutment, a firing-pin movable in said bore and provided with a sear-engaging lug projecting through said slot, a spring interposed between said pin and abutment, a sear adapted to normally engage said lug, a spring-pressed trigger, trigger-operated sear-displacing means, the slide being provided with an elongated face substantially perpendicular to the stem, and a slide-projecting device adapted to be set for action by the retraction of the slide and including a spring seated in the receiver, a bell-crank lever fulcrumed in the receiver and having arms of unequal length, and a link connecting the spring with the shorter arm of said lever, the longer arm of the lever being held by the spring in sliding contact with said face.

3. An automatic fire-arm comprising a barrel-containing and magazine-containing receiver, a slide movable in and guided by the receiver, a spring-pressed firing-pin movable relatively to the slide and provided with a sear-engaging lug, a resilient sear attached to the receiver and adapted to normally engage said lug, a spring-pressed trigger, and trigger-operated sear-displacing means including a spring-pressed finger pivoted to the trigger and adapted to be reciprocated thereby on a fixed finger-guiding portion of the receiver, and a bell-crank lever fulcrumed in the receiver, one arm of said lever

being engaged with the sear and the other arm projecting through said guiding portion in the path of said finger.

4. An automatic fire-arm comprising a barrel-containing and magazine-containing receiver, a slide movable in and guided by the receiver, a spring-pressed firing-pin movable relatively to the slide and provided with a sear-engaging lug, a resilient sear attached to the receiver and adapted to normally engage said lug, a spring-pressed trigger, trigger-operated sear-displacing means, and a safety device including a locking arm adapted to swing in the receiver into and out of the path of a member of said displacing means, and means operable from the exterior of the receiver for adjusting said arm, means being provided for preventing accidental movement of said arm.

5. An automatic fire-arm substantially as specified by claim 4, the said locking-arm being provided with a groove concentric with the axis on which it swings, and with a spring brake in said groove bearing yielding on the bottom of the groove and on the external surface of the receiver.

6. An automatic fire-arm comprising a barrel-containing and magazine-containing receiver provided with a guide at its rear end, a slide movable in the receiver and including a head and a stem projecting rearwardly from the head and movable in said guide, a slide-projecting device adapted to be set for action by the retraction of the slide, the slide stem being provided with a longitudinal slot, and the rear end of the receiver being provided with a fixed spring abutment projecting through said slot into the bore of said stem, a firing pin movable in said bore and provided with a sear-engaging lug projecting through said slot, a spring interposed between the pin and the said abutment, a resilient sear attached to the receiver and adapted to normally engage said lug, a spring-pressed trigger and trigger-operated sear-displacing means including a spring-pressed finger pivoted to the trigger and adapted to be reciprocated thereby on a fixed finger-guiding portion of the receiver, and a bell-crank lever fulcrumed in the receiver, one arm of said lever being engaged with the sear, and the other arm projecting through said guiding portion in the path of said finger.

7. An automatic fire-arm comprising a barrel-containing and magazine-containing receiver, provided with a guide and a fixed spring abutment at its rear end, a slide movable in the receiver and including a head and a stem projecting rearwardly from the head and movable in said guide, and provided with a longitudinal bore and a longitudinal slot receiving said abutment, a firing pin movable in said bore and provided with

a sear-engaging lug projecting through said slot, a spring interposed between the pin and said abutment, a sear adapted to normally engage said lug, a spring-pressed trigger,
5 trigger-operated sear-displacing means including a bell-crank lever fulcrumed in the receiver, one arm of said lever being engaged with the sear, and the other arm being movable by the trigger, and a safety device including a locking arm adapted to
10 swing in the receiver into and out of the path of the last-mentioned lever arm, and means operable from the exterior of the receiver for adjusting said arm, means being provided for preventing accidental movement of said arm.

In testimony whereof I have affixed my signature.

GIOVANNI MONGARDI.
